Primary Examiner — Robert M Spear*Assistant Examiner* — Eliza Bennett-Hattan(74) *Attorney, Agent, or Firm* — Kirk A. Buhler(57) **CLAIM**

The ornamental design for a wire spool guide, as shown and described.

DESCRIPTION

FIG. 1 is a top perspective view for a wire spool guide showing my new design;

FIG. 2 is a front side view thereof;

FIG. 3 is a back side view thereof;

FIG. 4 is a top side view thereof;

FIG. 5 is a bottom side view thereof;

FIG. 6 is a left side view, the right side view being a mirror image thereof;

FIG. 7 is a left sectional view taken along lines 7-7 from FIG. 4 thereof; and,

FIG. 8 is a top perspective view shown in an environment of use.

The broken lines in FIG. 8 depict environmental subject matter and form no part of the claimed design.

1 Claim, 5 Drawing Sheets**FIG. 1**

FIG. 2**FIG. 3**
